CLAIM

The ornamental design for an applicator, as shown and described.

DESCRIPTION

FIG. 1 is a front elevational view of an applicator showing our new design, the rear elevational view being identical; FIG. 2 is a right side elevational view thereof, the left side elevational view being identical;

FIG. 3 is a top plan view thereof;

FIG. 4 is a bottom plan view thereof;

FIG. 5 is a front elevational view thereof with the closure cap removed for clarity of illustration;

FIG. 6 is a top plan view thereof; and,

FIG. 7 is a bottom plan view of the closure cap shown in FIGS. 1-3 shown separately for clarity of illustration.
